POLISHING AND BUFFING WHEEL

Harry Zimmerman, Toronto, Ontario, Canada

Application June 26, 1950, Serial No. 170,456

1 Claim. (Cl. 51—193)

1

This invention relates to a buffing wheel and in particular to a method and means for forming a waved buffing wheel having dense columns to support the pressure of the lathe clamps and a waved formation extending throughout the width of the wheel.

Various methods for producing buffing wheels having a waved periphery have been proposed such as preforming the individual wheel sections to the desired waved shape, or by inserting between the sections or groups of sections preformed spacers. Typical examples of these means for forming waved buffing wheels are illustrated in U. S. Patents Nos. 2,044,858 and 2,187,602. The objection to both types of waved buffing wheels is that they are too compact between the lathe clamps and tend to produce a hard buffing or polishing surface; they are not adaptable for re-arrangement to change the shape of the wave on the periphery of the wheel.

An object of this invention is to provide a waved buffing wheel in which the buffing or polishing surface is brought to any density desired in any width wheel and which will have a longer life than those presently in use.

Another object of the invention is to provide a buffing wheel in which the waves are uniformly carried through to the periphery of the wheel regardless of its width.

These and other objects are accomplished, in the preferred construction, by providing wave forming elements which have the shape of a sector of a predetermined thickness and placing the buffing wheel sections between these sectors in a predetermined manner to form at least two diametrically opposite spaced apart dense columns arranged radially about the axis of rotation of the wheel. When the sections are pressed together by the lathe clamps which are used in mounting the assembled wheel on its spindle or shaft, the wave forming elements displace the buffing wheel sections from a single plane and compel them to form in two planes with the sides of the waves bridging and connecting the two planes.

For an understanding of the manner in which this invention is carried out and the waves formed in the buffing wheel, reference is to be had to the following description and the accompanying drawings in which:

Figure 1 is a plan view of the flexible spacer carrier having the same diameter as the lathe clamps with flexible wave forming elements for use between the lathe clamps and the wheel sections and inserted between the sections of the buffing wheels;

Figure 2 is a cross section through the vertical centre line of a pair of cooperating flexible carriers shown in Figure 1 in face to face relationship;

2

Figure 3 is a vertical cross section through the centre of a modification of the carrier with wave forming elements attached as shown in Figure 1;

Figure 4 is a vertical cross section through the centre of another modification of the carrier with wave forming elements attached as shown in Figure 1;

Figure 5 is a vertical cross section through the centre of still another modification of the carrier with wave forming elements attached as shown in Figure 1;

Figure 6 is a face view of a modification in which the wave forming elements are mounted on the buffing wheel sections and used for placing wave forming elements between the lathe clamps and the wheel sections, and also between the sections of the buffing wheel;

Figure 7 is a vertical cross section through the centre line of a pair of buffing wheel sections with wave forming elements attached as shown in Figure 6;

Figure 8 is a vertical cross section of a modified form of wave forming elements attached to the buffing wheel section as shown in Figure 6;

Figure 9 is a vertical cross section of another arrangement of wave forming elements attached to the buffing wheel section shown in Figure 6;

Figure 10 is a vertical cross section of still another arrangement of wave forming elements attached to the buffing wheel section shown in Figure 6;

Figure 11 is a vertical cross section of another arrangement of the wave forming elements attached to the buffing wheel section as shown in Figure 6;

Figure 12 is an enlarged cross section through the vertical line of a fluted buffing wheel to illustrate the application of the dense columns to support the pressure of the lathe clamps, and combined with the wave forming and pressure elements to a buffing wheel;

Figure 13 is a longitudinal cross sectional view taken on a vertical line through the centre of a completed waved buffing wheel with both outside ends flat and perpendicular to the axis of rotation of the wheel;

Figure 14 is a front view of the buffing wheel shown in cross section in Figure 13;

Figure 15 is a longitudinal cross sectional view of a wide face fluted buffing wheel with waves in the outside end sections; and

Figure 16 is a front view of the wheel shown in cross section in Figure 15.

In the drawings like letters of reference indicate corresponding parts in the different figures.

S represents a common buff section of any type made of material such as leather, felt, loose and stitched discs of cotton sheeting, and any other flexible material suitable for polishing and buffing.

R represents spacers of any flexible material

such as canvas of various thicknesses commonly used between sections in a buffering wheel; usually the diameter of the lathe clamps, and not requiring either vent or lacing holes when used in a wheel not laced, such as shown in Fig. 12. When used in laced wheels the spacers R are formed with indentations and lacing holes as shown in Figs. 1 to 5 and in Figs. 13 to 16.

M represents lathe clamps, as shown in Figs. 12 to 16.

L represents lacing and lacing holes, as indicated in Figs. 1, 6, 13 and 15.

a represents a flexible carrier produced by attaching flute forming elements to spacers R as shown in Figs. 1-4 and used as desired to form the dense columns AD shown in Figs. 12 to 16.

b represents a flexible carrier made like carrier a, and used in dense columns at right angles to carrier a as indicated in the left hand side Fig. 2, and used as desired to form the dense columns BD in a wheel as shown in Figs. 12 to 16.

f represents a flexible carrier like carrier a, but with two pressure elements attached at right angles to two other similar pressure elements, as shown in Fig. 5, and used where desired, as shown in Figs. 12 to 16.

A represents a carrier which is formed by attaching the wave forming elements direct to a buff section, as shown in Figs. 6 to 9 and used where desired in forming the dense columns AD as shown in Figs. 12 to 16.

B represents a carrier made of a buff section, with wave forming elements attached like carrier A, and used at right angles to carrier A as shown on the left hand side in Figure 7 and used where desired as shown in Figs. 12 to 16. Both carrier A and carrier B are used synonymously with buffering section S, when the latter section has wave forming elements attached.

F represents a carrier made of a buff section like carrier A but with two pressure elements at right angles to two other pressure elements on the same side of the carrier as shown in Fig. 10 and used where desired as shown in Figs. 12 to 16.

K represents a carrier made of a buff section like carrier A, but with two pressure elements attached to one side, and on the reverse side two other similar pressure elements attached at right angles, as shown in Fig. 11, and used where desired as shown in the enlarged Fig. 12 and Figs. 15 and 16.

AD and BD represent dense columns built up with the flute forming elements on the carriers a, A, in the dense columns AD, and the wave forming elements on the carriers b, B, in the dense column BD, either with the wave forming elements between the lathe clamps and the wheel sections, as shown on the right hand end in Fig. 12, or on both ends as shown in Fig. 15, or with buff section separating the lathe clamps from the wave forming elements as shown on the left hand end in Fig. 12, or on both ends as shown in Fig. 13.

In its simplest form, this invention consists of sector shaped wave producing elements mounted on a circular carrier having the same diameter as the lathe clamps which are ordinarily employed to press the buff sections together. I prefer wave producing elements of two different thicknesses, marked d, e, and two of such elements being placed diametrically opposite each other as shown in Figs. 1 and 6. At least two carriers are required for use in forming a waved wheel, one at each end thereof. One carrier is rotated 90° with respect to the other carrier so that the carrier on the right hand end produces what I call two dia-

metrically opposite dense columns AD, and the carrier on the left hand end produces two diametrically opposite dense columns BD located between the dense columns AD making four equally spaced dense columns of the same length arranged radially from centre of the buffering wheel and which support the pressure of the lathe clamps. The dense columns AD, under pressure of the lathe clamps, press the wheel sections to

10 the left and against the lathe clamp on the left hand end of the wheel. The dense columns BD press the wheel sections to the right and against the lathe clamp on the right hand end of the wheel. This forms what I term a balanced wheel, with perfect waves in the wheel sections, as shown in Figs. 12 to 16.

The most desirable carriers have the wave producing elements attached to spacers R which may be of any desired thickness, from very thin to very thick, and to buff sections S used as carriers as shown in Figs. 1, 2, 6 and 7. These figures show that the face of the wave producing elements are parallel with the face of the carriers and with the edges at right angles to the face.

20 In some cases it may be desirable to mount the wave producing elements on a rigid carrier or directly on the lathe clamps. Either construction places the wave producing elements between the lathe clamps and the wheel sections, 30 in which position they give the same results as the spacer carriers and the section carriers. In such cases the carriers place the wave producing elements between the lathe clamps and the wheel sections, and develop waves on the outside ends and on both sides of the wheel. In a wide wheel 35 all such carriers must be associated with some form of the wave producing or pressure elements or both, as shown in the detail drawings in Figs. 1 to 11.

40 The construction shown in Figs. 1 to 4 inclusive, consists of flexible carriers a, b having the same diameter as the lathe clamps, and made by adding wave forming elements d, e to separators R, such as are commonly used between buff sections in a buffering wheel. In Figs. 6 to 9 inclusive 45 the carriers are made of buff sections hereinafter referred to as section carriers. The wave producing elements de are mounted on each set of carriers in precisely the same position, namely the wave producing elements de on carrier b, Figs. 1, 2, and the wave producing elements de on carrier A are at right angles to the wave producing elements de on carrier B, Figs. 6, 7. In Figs. 2 and 7, I show these carriers with their wave producing elements in face to face relationship in 50 order that their proper position may be shown.

55 When used in a buffering wheel, the carriers are separated by the wheel sections. It will thus be seen that the face of carriers aA are separated from the face of carriers bB by the thickness of the flute producing elements de when combined in a buffering wheel. The elements de, under pressure of the lathe clamps, form a plurality of spaced apart dense columns, extending longitudinally and arranged in a circular pattern, about the axis of rotation. The dotted lines at the central portion from the top of flute forming elements de on carriers a or A to the top of wave forming elements de on carriers b or B, show the depth and angles to the sides of the waves in the wheel sections between the lathe clamps. The dotted lines at the central portion Figs. 2 and 7 show the same formation and depth of waves.

60 All carriers in a waved wheel, except those on the ends, are pressed into two planes, the same as

the wheel sections, and the elements attached to said carriers become a portion of the dense columns and are always in the same plane as the carriers in the dense columns, and therefore are parallel with the face of the lathe clamps, the same as the elements at the ends of the wheel.

It is often preferable to use relatively thick and thin wave producing elements in the same construction. Two modifications are illustrated in Figs. 3, 4 and Figs. 8, 9. In Figs. 3 and 8 I show the wave producing elements being made from the part *e* of the wave producing elements *de* in Figs. 1, 2 and 6, 7 and attached to carriers *aA* and *bB* respectively. In Figs. 4 and 9 the wave producing elements are made from the part *d* of the wave producing elements *de* in Figs. 1, 2 and 6, 7.

This combination of thick and thin wave producing elements gives a wide range for making fluted wheels having both straight and fluted sides, and with any depth of flutes desired in the working sections of the wheel. The flute producing elements *d*, as shown throughout these drawings represent one-half the thickness of the wave producing elements *e*.

It has been found that in a wide wheel, the effect of the wave producing elements at the ends of said wheel, the depth of the waves gradually get less toward the longitudinal center and finally disappear. This difficulty is overcome with a liberal use of wave producing elements and what I call pressure carriers, throughout the length of the wheel, so that the full depth of waves is carried through the entire face of the wheel regardless of its width. An additional advantage is that the depth of waves may be lessened or increased when desired in any portion of the wheel. Each pressure carrier has four pressure elements similar to the wave forming elements previously described, positioned 90° apart about the axis of rotation to form pressure carriers *f* and *F*, Figs. 5 and 10. The same results are obtained by taking carriers *aA*, Figs. 4 and 9 and placing them face to face with carriers *b*, *B* with the elements *d* positioned 90° apart.

Pressure carrier *K*, Fig. 11, is a modification of pressure carrier *F*, Fig. 10. In pressure carrier *K*, one pair of diametrically opposite elements *d* are attached to one face of the carrier and the other pair of elements *d* are attached to the opposite face on the diameter which is perpendicular to the diameter through the first mentioned pair. The same results are obtained by taking carrier *A* with elements *d* attached, as in Fig. 9 and placing it back to back with carrier *B*, with elements *d* positioned 90° from the wave producing elements *d* on carrier *A*. This construction is used usually in a waved wheel in which density is desired. Similar results are obtained with the use of spacer carriers *ad*, Fig. 4, and placing carrier *bd* at right angle to it, with buff section between the two carriers *ad* and *bd*. I call this construction, pressure carrier *k*, and it is applicable to where less density is desired in the wheel than given by pressure carrier *K*. All types of pressure carriers add the same thickness at the same time to the four dense columns, two dense columns *AD* and two dense columns *BD*. A desirable construction of the wave forming elements is obtained with the combination of wave forming spacer carrier *ad*, Fig. 4, with the wave forming spacer carrier *ae*, Fig. 3, by placing these two carriers with the elements of each carrier on the same diameter with buff section between said two spacer car-

riers *ad* and *ae* forming the construction shown in part 1, Fig. 12. A similar construction is made with section carriers *Ad*, Fig. 9, with a pair of wave forming elements *e* on the same diameter and on the reverse side of section carrier *Ad*. This construction with section carriers, gives greater density in a waved wheel, than the construction with spacer carriers. The enlarged Fig. 12 and Figs. 13 to 16 show various uses of the pressure elements and the wave producing elements and how these elements build up and form the aforesaid dense columns.

The spacer carriers and the section carriers are interchangeable, and several are often used, one superimposed on the other with buff sections between to get the depth of waves desired. The carriers, *a*, *b* and *A*, *B* are formed with lacing holes; the dotted lines in Figs. 1 and 6 diagrammatically depicting the lacing. Note that the lacing holes are grouped in a V formation, the lacing cord forms two loops around the outer ends of the dense columns, which not only holds the wheel securely together as a unit, but I have found that said formation is efficient, tightens very rapidly and is quickly performed. Lacing holes for the dense columns *AD* are on the vertical lines 5-5 and for the dense columns *BD* on the horizontal line 6-6. This places the dense columns *AD* 90° from the dense columns *BD* in a clockwise or anticlockwise direction as shown in Figs. 1 and 6.

Referring to spacer carriers made of spacers *R* for an unlaced wheel, I recommend small holes in position of the lacing holes, on the vertical line 5-5 as shown in Fig. 1, to be used for positioning the respective elements they carry, by threading a string through said holes, then draw it straight out to indicate the position of the elements, and when said elements are in proper position, withdraw the string before drawing the lathe clamps tight.

Fig. 6 shows V notches in the periphery of section carrier *A* on the vertical line 5-5, and at 90° therefrom are the V notches on the horizontal line 6-6. These V notches indicate markings on the carrier sections as means to assist, in an unlaced wheel, in the positioning of the elements in the dense columns *AD* for proper functioning with the elements in the dense columns *BD*. The rigid carriers and the spacer carriers are much alike, and I recommend that both types have markings to assist in positioning of the elements on the right hand end for proper function with the elements on the left hand end, as indicated for the spacer carriers, Figs. 1 and 2.

All carriers from Figs. 1 to 4 and from Figs. 6 to 9, show two elements diametrically opposite each other on the same carrier, one on each side of the centre, and the construction individually is in balance. It is obvious that a carrier made with one wave producing element in position on the centre line, as an individual carrier, would be out of balance, but by placing two such carriers in a wheel, with the wave producing elements of each carrier on the same diameter but at opposite ends of said diameter and on opposite ends of the wheel, said wheel would be in balance and have two dense columns, *AD* and *BD*, of the same length, supporting the pressure of the lathe clamps. Such a wheel built with the use of pressure elements, two pressure elements on the same diameter may be built with any width face desired.

The most desirable construction is built with

two wave producing elements on each carrier. These produce four dense columns in a wheel, and they all must be built up to the same total length. It is clear that some of the wave producing elements may be widened and extended to the periphery of the working face of the wheel sections, such elements should be incorporated in a buff section, and become a part of the working portion of a section, but they in no way affect the wave producing functions of said elements.

Spacer carriers have long life, as they are in no way injured by the work performed by the wheel, and they are used repeatedly over and over again. The section carriers are limited to the life of the wheel sections. When rigid wave producing elements are mounted on rigid carriers or on the face of the lathe clamps, such carriers have indefinite length of life, but they are limited to the construction that places the wave producing elements between the lathe clamps and the wheel sections, forming only a wheel with waves on the outside ends. However, they are used in combination with both the spacer carriers and the section carriers with flute producing and pressure elements attached, to control and insure the depth of waves throughout the width of a wide wheel.

Fig. 12 is an enlarged cross section view of a waved buffing wheel. The construction on the left hand end shows a buff section between the lathe clamp and the wave producing elements, forming the make up of a waved wheel with the outside ends running in one plane. On the right hand end, with the wave producing elements between the lathe clamp and the wheel sections, showing the make up of a fluted wheel with the outside ends waved. This construction brings out the dense columns AD formed by the wave producing and pressure elements in the vertical line on the right hand end, and dense column BD formed by the wave producing and pressure elements in the horizontal line on the left hand end. Note how the dense columns AD push all sections and intervening elements between the lathe clamps towards the lathe clamp on the left, forming two dense columns without any vacant places, and on the left the dense columns BD push all sections and intervening elements between the lathe clamps towards the lathe clamp on the right, forming dense column BD without any vacant places. In the drawing we see only dense column BD, as the top of the sections go straight out to the periphery.

Note the vacant places on the edges of the dense columns, through the entire central portion of the wheel between the dense columns under the lathe clamps, formed by the various pressure and wave producing elements that enter into the make up of the wheel. The vacant places formed by the various elements are in proportion to the thickness of the elements that make them.

It is obvious that the various wave forming and pressure elements sink partly into the wheel sections, which bulge up and absorb a portion of the vacant spaces they create, and the vacant spaces as shown in the drawings diagrammatically depict the vacancy and necessity of using the pressure carriers liberally.

The F and f type of pressure elements function as spacers, with no pressure on the sides of the flutes in the wheel sections, while the K and k type of pressure elements function as flute forming elements, as they cause the changing of the depth of waves in the carriers, but do not change

the depth of waves in the wheel sections. All of the pressure and wave forming elements have contact in the dense columns only, and the space between the dense columns has no contact and hence no pressure.

The four dense columns, two columns AD and two columns BD are all of the same length and support the pressure of the lathe clamps. Attention is called to the fact that waves generated by the columns AD envelop and fold over the various elements, and the same is true of the waves generated by the columns BD. This has the effect of locking the dense columns together in one position and the wheel cannot twist after the lathe clamps are drawn tight, which is a common difficulty in an ordinary buffering wheel.

The waved buffering wheel shown in Fig. 12 is divided into five parts, designated by the numerals 1, 2, 3, 4 and 5, in which all the elements shown in Figs. 1 to 11 are employed, to illustrate the way they may be used to decrease or increase the depth of waves, or to maintain the depth of flutes unchanged, through the wheel, regardless of its width. Part 1 shows a buff section S between the lathe clamp and the wave producing elements, producing a waved wheel with the outside ends flat and running in one plane. The wave producing elements d immediately follow the buff section S next to the lathe clamp; then a second buff section S followed with the wave producing elements e which brings the waves to the full depth of the combined wave producing elements d and e, as shown by the waves in the third buff section S from the lathe clamp on the left hand end of the wheel. This is more fully brought out in Figs. 13 and 14. Part 2 shows construction with deep waves. Part 3 shows how the flute producing elements ad to the left, in the dense column AD, lessen the depth of waves in the sections and at the same time use the pressure carrier f as seen in each dense column. Part 4 again shows the flute producing carrier ad to the left, in dense columns AD and how it subtracts from the depth of waves. To the left in part 5, in dense column BD is flute producing carrier be, which immediately brings the depth of waves back to that shown under part 2. Then come the pressure carriers F and K which show clearly in dense columns, and on the right hand end of part 5 is the flute producing carrier Ade, which places the wave producing elements de between the lathe clamp on the right hand end and the wheel sections, forming waves in the outside section of the wheel as brought out in Figs. 15 and 16.

Fig. 13 is a cross section illustrating a waved wheel with the end buffering sections engaged between the lathe clamps and the flute producing elements resulting in a wheel with straight ends and suitable for hand work. This wheel is made with the same wave producing elements and in the same order as shown in Figure 12 under part 1. This produces a wheel of soft density. It is clear that if wave producing elements Ad, Fig. 9, and Ae, Fig. 8, were used leaving out the spacers R, and using pressure carrier K, Fig. 11, we would get a very dense wheel, entirely too hard for ordinary work. The range from very soft to very hard is great, but all involves the dense columns AD and BD which carry the pressure of the lathe clamps and permit all elements in the AD side of the wheel to perform their functions with the cooperating elements in the BD side of the wheel.

Fig. 14 is a front elevation of the finished fluted wheel shown in the cross section in Fig. 13. The

flutes in the working face of the various sections are affected by the several flute producing and pressure elements as shown in said drawing. A laced wheel in one unit does not require any marking, as the lacing holes properly position the elements in the AD side for their function with the elements in the BD side.

Figs. 15 and 16 illustrate another assembly of the wave forming elements and pressure carriers. This wheel is made in five distinct parts 1, 2, 3, 4 and 5, all running on one spindle as a single wheel. Part 1 has wave forming elements *de* between the lathe clamp and the wheel sections, no spaces between the sections *S* except pressure carrier *K* which presses the carrier section at the elements *d*, two places on the AD side and two places on the BD side. This part 1 makes an exceptionally hard wheel. Part 2 shows two pressure carriers *F* and single spacers *R* between the sections *S*, the waves are full depth as shown in part 1. This part 2 is moderately dense. Part 3 starts out with deducting elements *ad* from the depth of the waves otherwise it is the same as part 2. Part 4 again starts out by deducting elements *ad* from the depth of the waves and shows that the depth of the waves in part 4 is less than in part 3. Part 4 also includes a pressure carrier *f* which adds to the length of the dense columns, the same as shown for the pressure carriers *F* in part 2. Part 5 starts out by adding the wave forming elements *de* and at once increases the depth of the waves to the same as in parts 1 and 2, then at the end is the wave producing carrier *Ade* which places the wave producing elements *de* between the lathe clamp and the wheel section *S* the same as shown in Fig. 12 under 5. Also note the carrier *f* and two spacers *R* between the sections *S*. This is very soft but also effective because of the deep waves it carries. Both ends of this wheel (Fig. 15) have the wave producing elements between the lathe clamps and the wheel sections *S* which produce the waves on the outside ends of the wheel and suitable for automatic buffering machine work.

Parts 1 to 5 represent only a portion of the wide range of density in cutting quality possible in a wide wheel. Further it is clear that any one part may extend through the entire width of the wheel, and the waves in any portion of said wheel may be decreased or increased as desired for any special work required for said portion of a wheel. The depth of waves affect the cutting quality of a wheel entirely independent of the stitching in the sections. For easy handling and mounting of a wide face wheel on the latter spindle, I recommend the dividing of the wheel

into smaller units and the lacing of said units and in an unlaced wheel, tack the units together through the dense columns. All units are marked for assistance in assembling the several units in their respective position in a finished wheel.

Fig. 16 shows the effect on the working face of the sections for the parts 1 to 5 as set up in the cross section view Fig. 15. In part 1 there are no spaces except for the pressure elements 10 *K* which press against the adjoining sections in four places, all other sections are tight together and part 1 is very dense. Part 2 with two pressure carriers *F* and single spacers between the sections, with the depth of waves the same as in part 1. Part 2 is moderately hard. Part 3 is much like part 2 but a little softer. Part 4 is close to part 3 but again a little softer than part 3. Part 5 is soft and rapid working due to the deep waves and the wide spacers.

What I claim as new and desire to protect by Letters Patent of the United States is:

A buffering wheel comprising in combination a plurality of flexible buffering sections each having the general form of a centrally perforated normally flat circular plate, a pair of complementary flexible fabric carriers for confining between them a group of said buffering sections, each carrier having the general form of a centrally perforated normally flat disc and having a diameter substantially less than the said buffering sections, fabric wave forming elements mounted on each carrier and positioned so that the wave forming elements of one carrier register centrally in a circumferential direction between the 25 wave forming elements of its complementary carrier, each wave forming element having the general form of a sector shaped flat member truncated towards the center of the carrier and being of the same predetermined thickness throughout, with means for pressing the buffering sections, the carriers and the wave forming elements mounted thereon together to form a buffering wheel having a wave formation on the periphery of the buffering wheel.

HARRY ZIMMERMAN.
